ALBUM PICTURE HOLDER

Abraham Holtzman, New York, N. Y.

Application September 30, 1944, Serial No. 556,624

4 Claims. (Cl. 129--20)

1

This invention relates to album picture holders. One object of the invention is to provide an album picture holder having improved means for mounting pictures in a permanent manner.

Another object of the invention is the provision of improved means for movably but permanently mounting pictures so that notations placed on the back thereof may be conveniently inspected.

Another object of the invention is to furnish improved means of a strong and durable character adapted for adhesive connection to a leaf in an album and having adhesive portions whereby a number of pictures can be movably, permanently mounted with the pictures partially overlapping each other in a neat, attractive and highly compact manner.

Another object of the invention is to provide improved means comprising picture holding tabs having nontacky gummed faces and consisting of linen perforated to provide fold lines but being otherwise stiffened by the gum coating.

Another object of the invention is to furnish an improved unitary tab structure wherein the tabs are adhesively mounted on a backing in such a manner that each tab protects an adjacent tab against inaccurate securement to the backing, with certain portions adapted to provide gummed sections at the rear of the backing for mounting the tab structure on an album leaf.

Another object of the invention is to provide improved methods and means whereby a multi-tab picture mounting is cheaply, accurately, and rapidly constructed and assembled.

Other objects and advantages of the invention will become apparent as the specification proceeds.

With the aforesaid objects in view, the invention comprises the novel features, combinations and arrangements of parts hereinafter described in their preferred embodiments, pointed out in the subjoined claims, and illustrated in the annexed drawing, wherein like parts are designated by the same reference characters throughout the several views.

In the drawing:

Figure 1 is a fragmentary perspective diagrammatic view showing an album picture holder embodying the invention, with pictures shown in dot-dash lines.

Fig. 2 is an enlarged front view of one of the picture holding units of Fig. 1 according to the invention.

Fig. 3 is a rear view of the unit.

Fig. 4 is a fragmentary greatly enlarged edge 55 by a thin coating of a water soluble glue when

2

view of the unit, with parts of attached pictures shown in dot-dash lines.

Fig. 5 is a fragmentary view of a tab element, illustrating a step in the method of making the picture holding unit.

Fig. 6 is a perspective fragmentary view of a backing sheet with a bottom tab element marginally applied according to the next step of the process.

Fig. 7 is a similar view showing the next step of applying a picture holding tab adjacent to the marginal element.

Fig. 8 is a plan view showing the application of the remaining picture holding tabs and of a top marginal element, the latter being ready to be folded down to complete the blank for cutting along vertical lines to produce the units of Figs. 1 to 3.

The advantages of the invention as here outlined are best realized when all of its features and instrumentalities are combined, but useful embodiments may be produced involving less than the whole.

It will be obvious to those skilled in the art to which the invention appertains, that the same may be incorporated in several different constructions. The accompanying drawing, therefore, is submitted merely as showing a preferred exemplification of the invention.

Referring in detail to the drawing, 10 denotes a device embodying the invention, comprising an album book 11 on a leaf of which are adhesively mounted a plurality of picture holding units 12, certain pictures mounted thereon being indicated in dot-dash lines at 13. Each unit 12 provides a series of leaves 14 to the front faces of which the pictures are connected. These leaves are mounted at different elevations, so that the pictures overlap each other. Each leaf is foldable up and down so that certain overlapping pictures can be swung upward to expose a selected picture thereunder. Thus a neat and highly compact mounting is obtained.

More specifically, each unit 12 includes a backing sheet of paper or other flexible material 15, to the front face of which is secured a series of elements 16, each consisting of linen or other suitable textile. The front face of each element 16 is coated with a non-tacky gum adhesive, or the like, which impregnates the textile and stiffens the same. This coating is softened by wetting to permit a picture to be secured to its tab portion 14. The rear face of each tab element 16 is adapted to be connected to the backing 15 by a thin coating of a water soluble glue when

applied at a temperature of 130 to 150 degrees F., which is sufficient for quick adhesion but not so hot as to render the gum coating tacky. The 5 secured by the glue is at the upper portion 11 of each element 16. To properly define a line of folding, each element 16 is formed with a perforated line 18 as more clearly shown in Fig. 5, whereby an easy hinge action is obtained for the depending tab 14. By reason of this line of perforations, the elements 16 may be secured to the backing 15 without danger of the tab 14 sticking, as hereinafter described. The backing 15 is completely concealed and covered by the 10 gummed elements 16, whose sections 17 abut each other at the perforated lines 18, with each section 11 underlying an adjacent tab portion 14 of another element 16, thus assisting in the accurate gluing to the backing as hereinafter described. Further, when a tab 14 is lifted, a uniform 15 appearance is noted because of the concealment of the backing, and the latter is protected from accidental cutting or breakage by the substantially stronger sections 17. The abutment 20 of sections 17 at the lines of perforation 18 may afford a slight lifting of the tabs 14 so that the latter are easily engaged, if necessary. At the 25 bottom edge of the backing 15 is a binding 19 which may consist of an element 16 folded so that its sections 19a and 19b are respectively adhesively secured to the front and rear of the 30 backing, the section 19a underlying a tab 14 and abutting an element 16 at its line of perforations. A very thin line in the binding 19 is possible because it is folded along its central line of perforations 18. At the top edge of the backing, a binding strip 20 consisting of an element 16 is likewise centrally folded on its line of perforations 18 and its sections 20a and 20b respectively lying at the front and rear of the backing, with the section 20a forming a picture holding tab 35 extending down to the adjacent line of perforation 18 and overlying the adjacent section 17. The rear section 20b, and the sections 19a and 19b are pasted to the backing 15 by the water 40 soluble glue hereinabove mentioned, the gummed faces of the elements 19 and 20 being external. Thus uniformity of appearance is maintained and the process of manufacture facilitated as later 45 explained. Furthermore the gummed faces 19b and 20b at the rear of the backing 15 may be merely moistened and thus secured to a leaf of the album 11 to thus mount a unit 12 therein.

The process of manufacture will now be described. Preferably the units 12 are made in long sections which are transversely severed to 50 produce the units 12. Thus the strips 16a, as shown in Fig. 5, may be several feet in length. As already stated they consist of textile, gummed on one side as at 16b, with the other side 55 16c plain, each strip being centrally perforated at 18. Now a long backing sheet 15a is prepared whose width is equal to the length of the sheet 15. An element 16a is applied to the entire length of the bottom edge of the sheet 15a to form a binding strip 16d like that at 19. Next an element 16a 60 is applied as in Fig. 7 for the entire length of the sheet 15a to produce an element 16e, like that at 16; and additional elements 16e are applied as in Fig. 8 up to the top edge of the backing. Then an element 16a is applied as a top binding 65 16f like that at 20, and its section 16g is then folded down like that at 20a. Finally the structure is cut along vertical lines to produce the finished units 12.

Certain details in the gluing will now be de-

scribed. It is essential that the elements 16a shall not become stuck to the backing sheet 15a except at their sections above their perforated lines, but those sections must be strongly uniformly pasted down. The difficulties are aggravated as the glue has a tendency to spread. My process affords a solution to these problems, because each element 16 applied affords an easy control for a succeeding element. Reverting to Fig. 4, it will be noted that in process of manufacture, the lowermost tab 14 could not stick to the backing because of the underlying section 19a. Similarly, every section 17 protects its overlying tab 14, whereby the pasting of the elements 16 to the backing 15 is greatly facilitated. In this regard, it will be noted that the sections 17 never become wetted through, and in fact the gum adhesive on their front faces prevents this. It will also be perceived that edges or lines of perforations of different elements pasted on afford lines of indicia for accurately positioning the different elements.

The unit 12 embodying the invention is a complete article wherein the tabs 14 afford a mounting of permanent character for a series of pictures which are readily pasted to successive tabs by wetting. This mounting is movable so that the pictures can be swung upwardly about the perforated hinge lines to expose any selected picture and to permit inspection of names and dates that may be marked on the rear of a picture. The textile tabs are sufficiently strong to prevent accidental tearing thereof even at the lines of perforation, and in fact they reinforce the pictures at their upper edges. Pictures considerably wider than a unit 12 may be similarly mounted. No jar of paste or glue is needed for mounting the pictures or the entire unit. For the latter purpose, only the sections 19b and 20b need be wetted. There is nothing tacky to handle, except one momentarily wetted gummed section. The unit 12 is reliable and compact, and pictures cannot accidentally drop out as in the case of other devices currently used to mount pictures in an album.

I claim:

1. An album picture holder comprising a backing member and a vertical series of strip elements consisting of a textile fabric, each having a central line of weakness defining upper and lower sections, each strip element having on only one face thereof a coating of a non-tacky gum that is rendered adhesive by wetting with water, the elements being connected at their other face to said backing member by a water soluble glue applied only at their upper sections without affecting the gum coating, and the lower sections of the strip elements being adapted to fold upon the lines of weakness outwardly of the backing member, the strip elements being so arranged that the lower section of one element overlies the upper section of an adjoining element with the top edge of said upper section coinciding with the line of weakness of the adjacent upper element, one of the elements forming a binder for the top edge portion of the backing member and having its line of weakness at the top edge of the backing member with the relatively upper section of said element downwardly folded and secured to the rear face of the backing member for mounting the latter upon wetting the non-tacky gum coating of the downwardly folded portion.

2. A picture holder comprising a backing member, and a vertical series of strip elements consisting of a textile coated on only one side with

a non-tacky gum which becomes adhesive upon wetting with water, said coating stiffening the elements, each element having a central line of perforations defining upper and lower sections, only the upper sections being secured at the other side thereof to the backing member by a water soluble glue, the elements being so arranged that a lower section of one element freely overlies an upper section of the next lower element with the upper edge of said upper section abutting the upper section of the next higher element at the line of perforations of the latter, and marginal strip members for the upper and lower edges of the backing member having on only one face a coating of a non-tacky gum adapted to become adhesive upon wetting with water which coating stiffens the strip members, each strip member having a central line of perforations, the member for the lower edge being folded on the line of perforations and having portions at different sides of said line secured to the front and rear of the backing member by a water soluble glue, with one of the portions underlying the bottom section of a strip element, and the strip member for the upper edge being folded on the central line of perforations with a portion at one side of the line being secured to the rear of the backing member by a water soluble glue and the portion at the other side of said line overlying the top section of an adjacent strip element, the glue being applied to the uncoated faces of the portions of the strip elements and members secured to the backing member, whereby the coated portions at the rear of the backing member serve for mounting the holder on an album page and the coated portions of the strip elements and of the upper strip member are adapted for mounting pictures.

3. A picture holder having a backing member, strip elements consisting of textile fabric having 40 on their outer faces a stiffening coating of non-

tacky gum adapted to become adhesive upon wetting with water, all of the strip elements being of like size and shape and each having a central line of perforations, said strip elements being adhesively connected at their inner faces to the backing member, a series of the strip elements being connected to the backing member only at their sections that lie above their lines of perforations so that their lower sections are free to fold outwardly about said line, the lower section of each of said elements overlying the upper section of the respective next lower element, certain other of said elements being connected to the backing member at the rear face thereof with their lines of perforations lying respectively at the top and bottom edges of the backing member with a section of the top element being folded downwardly to freely overlie an adjacent top section, and a section of the bottom element underlying an adjacent bottom section and being free thereof but being adhesively connected to the front face of the backing member.

4. A device including a backing member and a series of identical separate strip elements certain of which constitute picture mounts and the others constitute combined binding and mounting means for securing the backing member to an album leaf, the picture mount elements being folded and secured to the backing member at one face thereof in overlapping tab forming relation to each other, the elements of said means being folded over and secured to the different end portions of the backing member and providing an overlapping relation with adjacent picture mount elements, portions of the folded elements being at the opposite face of the backing member, said portions and the tabs being corresponding sections of the elements coated with a non-tacky cement that becomes adhesive upon wetting.

ABRAHAM HOLTZMAN.
